CLAIM

The ornamental design for a pan with a utensil retention feature, as shown and described.

DESCRIPTION

This Design Application is also related to co-pending U.S. Design patent application Ser. No. 29/428,184, filed on Jul. 27, 2012, entitled Bowl With Utensil Retention Feature; U.S. Design patent application Ser. No. 29/428,185, filed on Jul. 27, 2012, entitled Bowl With Utensil Retention Feature; U.S. Design patent application Ser. No. 29/428,187, filed on Jul. 27, 2012, entitled Bowl With Utensil Retention Feature; U.S. Design patent application Ser. No. 29/428,188, filed on Jul. 27, 2012, entitled Bowl With Utensil Retention Feature; U.S. Design patent application Ser. No. 29/428,189, filed on Jul. 27, 2012, entitled Bowl With Utensil Retention Feature; U.S. Design patent application Ser. No. 29/428,215, filed on Jul. 27, 2012, entitled Bowl With Utensil Retention Feature; U.S. Design patent application Ser. No. 29/428,221, filed on Jul.

27, 2012, entitled Bowl With Utensil Retention Feature; U.S. Design patent application Ser. No. 29/428,225 filed on Jul. 27, 2012, entitled Bowl With Utensil Retention Feature; U.S. Design patent application Ser. No. 29/428,227, filed on Jul. 27, 2012, entitled Bowl With Utensil Retention Feature; U.S. Design patent application Ser. No. 29/428,232, filed on Jul. 27, 2012, entitled Bowl With Utensil Retention Feature; U.S. Design patent application Ser. No. 29/428,240, filed on Jul. 27, 2012, entitled Bowl With Utensil Retention Feature; U.S. Design patent application Ser. No. 29/428,244, filed on Jul. 27, 2012, entitled Bowl With Utensil Retention Feature; U.S. Design patent application Ser. No. 29/428,248, filed on Jul. 27, 2012, entitled Bowl With Utensil Retention Feature; U.S. Design patent application Ser. No. 29/428,253, filed on Jul. 27, 2012, entitled Bowl With Utensil Retention Feature; U.S. Design patent application Ser. No. 29/428,256, filed on Jul. 27, 2012, entitled Bowl With Utensil Retention Feature; U.S. Design patent application Ser. No. 29/428,261, filed on Jul. 27, 2012, entitled Bowl With Utensil Retention Feature; U.S. Design patent application Ser. No. 29/428,270, filed on Jul. 27, 2012, entitled Bowl With Utensil Retention Feature; and U.S. Design patent application Ser. No. 29/428,276, filed on Jul. 27, 2012, entitled Bowl With Utensil Retention Feature; and U.S. Design patent application Ser. No. 29/428,279, filed on Jul. 27, 2012, entitled Bowl With Utensil Retention Feature. The disclosure of these Design Applications are considered part of and are incorporated by reference in the disclosure of this design application.

FIG. 1 is a top perspective view showing a pan with a utensil retention feature;

FIG. 2 is a front view of the of the pan with the utensil retention feature of FIG. 1;

FIG. 3 is a back view of the pan with the utensil retention feature of FIG. 1;

FIG. 4 is a side view of the pan with the utensil retention feature of FIG. 1;

FIG. 5 is another side view of the pan with the utensil retention feature of FIG. 1;

FIG. 6 is a top view of the pan with the utensil retention feature of FIG. 1; and

FIG. 7 is a bottom view of the pan with the utensil retention feature of FIG. 1; and,

FIG. 8 is an enlarged, broken away view of area 8 on FIG. 1. The broken lines of the preceding FIGURES are for illustrative purposes only and form no part of the claimed design.
